[57] CLAIM

The ornamental design for a beach bag, as shown and described.

DESCRIPTION

FIG. 1 is a top, front and left side perspective view of a beach bag showing my new design;

FIG. 2 is a front elevational view thereof;

FIG. 3 is a rear elevational view thereof;

FIG. 4 is a side elevational view thereof, the opposite side being identical to the side shown;

FIG. 5 is a top plan view thereof; and

FIG. 6 is a bottom plan view thereof;

The fragmentary broken line representation of a towel or beach blanket is for illustrative purposes only and forms no part of the claimed design.
